UNITED STATES PATENT OFFICE

WILLIAM HEWIG, OF BATTLE CREEK, MICHIGAN, ASSIGNOR TO H. B. SHERMAN MANUFACTURING COMPANY, OF BATTLE CREEK, MICHIGAN, A CORPORATION OF MICHIGAN

MIXING LAUNDRY FAUCET

Application filed February 24, 1930. Serial No. 431,024.

This invention is a novel improvement in so-called "mixing laundry faucets" and "double laundry tray faucets" in which the hot and cold water pipes are connected to a twin faucet body having a common outlet connected with a swingable spout and ordinarily provided with supporting brackets whereby the faucet can be readily attached to a laundry tub or other suitable support and maintained in proper position without interfering with the interior of the tub.

Ordinarily to avoid the expense and hazards in foundry work these brackets are formed separately from the body and secured thereto by screws or bolts, which frequently loosen and permit the body to become detached from the brackets or allow the faucet to rattle after installation.

The present invention provides novel means for connecting the supporting legs or brackets to the faucet body and enables the brackets to be cast separately from the body and thereafter rigidly and inseparably secured to the body, without the use of bolts or rivets; and also whereby drilling or machining of the body or the brackets to enable them to be connected will be unnecessary. In accordance with my invention the body is formed with projecting lugs adapted to fit the complementary ends of the brackets, one of the complementary members having projecting malleable flanges which when the parts are fitted together are bent over the lugs and secure the brackets rigidly and inseparably to the body.

In the accompanying drawings I have illustrated one practical embodiment of the invention and will describe the same with reference thereto, and then summarize in the claim the novel features of construction and novel combinations of parts for which protection is desired.

In said drawings—

Fig. 1 illustrates one form of mixing laundry faucet provided with supporting brackets connected thereto in accordance with my invention.

Fig. 2 is an enlarged perspective view of a portion of the body showing one of the bracket engaging lugs.

Fig. 3 is a similar perspective view of the lug-engaging end of the bracket with the retaining flanges distended.

Fig. 4 is a perspective view showing the parts in Figs. 2 and 3 united, and the retaining flanges folded down.

Fig. 5 is a vertical section on the line 5—5 Fig. 4.

Fig. 6 is a transverse section on the line 6—6 Fig. 4.

The laundry faucet or body may be of any suitable construction. In the construction shown it has a U-shaped body having at one end a hot water inlet H, and at the other a cold water inlet C and an intermediate common outlet connected to a spout S; and suitable valves V are interposed between the hot water inlet and the outlet, and between the cold water inlet and the outlet. This body is shown as supported by brackets B upon the edge of a tub or other suitable support. The parts thus far described being well known require no detailed description as my invention relates to the novel means whereby the separately cast brackets B may be firmly and indetachably attached to the faucet body.

In accordance with my invention the body is provided at opposite sides of the outlet with lugs 1 each of which may be approximately an inch in length and is preferably 70 triangular in transverse cross section, the apex of the triangle being innermost and pointing toward the outlet and the base of the triangle being outermost. The outer edges of the lug at the base of the triangle are notched 75 as at 1a for engagement by retaining flanges 2a on the brackets as hereinafter referred to.

The end of each brackets B is provided in its inner side with a recess 2 preferably angular in transverse cross section and complementary to the angular end of the lug 1 which it is adapted to receive, as indicated in the drawings; and at opposite sides of the recess are malleable flanges 2a which, after the lug 1 is entered in the recess are turned down over the outer face of the lug 1 and into engagement with the notches 1a, as indicated in Figs. 4 and 5. When thus engaged the flanges 2a bind the brackets B securely to the lug 1 and as the flanges engage the notches 1a they ef- 100

fectively prevent longitudinal play or any movement of the bracket relative to the lug, and it is impossible for the brackets to become detached from the body unless the parts should break.

5 This construction is practically as solid and rigid as if the body and brackets had been cast integral. The lugs and ends of the brackets are complementary and each so shaped that it can be readily cast or formed as a part of the body or of the bracket as desired. Preferably the flanges are cast on the bracket as that construction is found more convenient in assembling the parts and in 10 closing the flanges upon the lug; but obviously the lugs might be shaped like the ends of the brackets and the ends of the brackets shaped like the lugs, and the complementary parts would be similarly interlocked and connected as above described.

15 The invention enables the body and brackets to be cast separately and to be rigidly connected together expeditiously and securely. The angular shape of the lug and complementary angular shape of the recess insure that 20 the brackets will be properly located and positioned relative to the body when the parts are connected as above described.

25 I do not consider my invention limited to 30 the specific form and arrangement of the bracket and interlocking complementary lugs and brackets illustrated in the drawings; but that is the present preferred and practically satisfactory and efficient construction.

35 I claim:

36 In combination; a member whose end is angular in cross-section and provided with notches in two edges of its angular portion; a second member having an end provided 40 with an angular recess shaped to receive the angular notched end of the first member, and having foldable flanges at opposite sides of the recess adapted to be folded over the first member and in engagement with the said 45 notches to form a substantially rigid permanent connection between said members when they are properly interengaged.

WILLIAM HEWIG.
